IMPREGNATING MACHINE

Carl W. Zies, Lakewood, Ohio, assignor, by mesne assignments, to The V. D. Anderson Company, Cleveland, Ohio, a corporation of Ohio

Application January 19, 1945, Serial No. 573,494

5 Claims. (Cl. 127—1)

1
This invention relates to continuous screw presses, and more particularly to presses specially designed or adapted for use in impregnating certain cellulosic materials with acid for the purpose of hydrolysis in processes for the production of sugar or alcohol, or for analogous uses. In such processes suitable cellulosic material, such as corn cobs, is sprayed or otherwise wetted with dilute acid, and is then subjected to pressure at an appropriate temperature for the desired period. The process requires means for applying pressure to the material and for either heating or cooling it, all preferably continuously with constant progression of the raw material through the apparatus, and with the ability to control temperature.

The present invention has for its object to provide simple and convenient apparatus, of screw press form, suitable for the purpose, such apparatus including a pressure screw rotating on a vertical axis and provided with improved means for driving it, for supporting the weight of the parts, for taking care of the endwise thrust, for supplying the raw material and removing the finished product, for controlling the temperature by supplying either a heating or a cooling effect, and for compelling advance of the material through the machine.

Still another object is to provide improved apparatus of the character described which is of simple form involving relatively few parts, all of which are durable and not likely to get out of order in service, the entire machine being quite compact and requiring minimum floor space.

Further objects of the invention in part are obvious and in part will appear more in detail hereinafter.

In the drawings, which represent one suitable embodiment of the invention,

Fig. 1 is a sectional elevation through the upper half of the machine;

Fig. 2 is a similar section through the lower half of the machine;

Figs. 3, 4 and 5 are sectional plan views taken respectively on the lines 3—3, 4—4, and 5—5, Fig. 2;

Figs. 6 and 7 are sectional plan views on the lines 6—6, and 7—7, Fig. 1; and

Fig. 8 is a detail elevation of a portion of the machine, viewed from the bottom of Fig. 7.

The apparatus selected for illustration in the drawings, comprises a frame including a base 1 adapted to rest upon the floor or other support and provided with several, three being shown, channel form columns or posts 2 on which are mounted an upper head or platform 3 to support

the driving motor 4 and other parts, and several plate like horizontal shelves 5, 6, 7, the latter carrying a sloping discharge plate 8 lying between two parallel side plates 9 and adapted to receive the solid residue and discharge it forwardly, or to the left in Fig. 2. Plate 7 also supports a heavy metal guide or bearing sleeve 10.

Posts 2 may bottom on the base 1, as shown, so that the entire machine is above the floor level, or, if desired the base 1 may be attached to posts 2 at any point intermediate their upper and lower ends, with the central portion of the base cut away to receive the other parts of the machine, thus permitting the machine to be supported from the floor above and to extend downwardly through a floor opening into the room beneath.

Rigidly secured, as by welding, in openings in the several shelves, and extending along a vertical axis centered between the several posts 2 are inner and outer concentric imperforate tubes or barrel members 11, 12, spaced apart to provide an annular cavity or space 13 between them. The inner tube is fairly thick and strong, to withstand pressure, but the outer tube may be of thinner metal since it serves only as a jacket.

Barrel member 11 extends above the head or platform 3 and supports a disc 11a on which is rigidly mounted suitable transmission mechanism shown conventionally at 14. This may include bevel or other gearing and change speed devices, if desired (not shown), for transmitting power at any desired speed ratio from the horizontal input shaft 15 to the vertical output shaft 16. Input shaft 15 is driven by motor 4, the shaft 15 of which is provided with a sprocket 18 connected by chain 18a to a sprocket 19 on shaft 15.

If desired, the transmission mechanism may be of simpler form, omitting change speed gears, and speed changes may be secured by changes in the sizes of the two sprockets 18, 19, or by using a change speed motor, all as will readily occur to one skilled in the art.

The lower end of output shaft 16 enters and bottoms in a recess or socket in a solid plug 20 welded into the upper end of a tubular feeder shaft 21 and is suitably connected to drive said shaft, as by a key or the cross pin 22 shown. This feeder shaft is located concentrically with an within barrel member 11, but is smaller, leaving an annular space 23 closed at its upper end by plate 11a and in which are located a series of spiral vane flights 24 welded to shaft 21 and spaced length wise thereof. Each vane flight 25 makes one or more turns around the shaft axis

and the trailing edge of each is spaced, longitudinally of the shaft, from the leading end of the next, leaving a gap between each two vane flights to receive an abutment member, such as a stationary knife or pin 25. As shown the first flight 24a extends about $2\frac{1}{2}$ turns about the axis and has a relatively quick pitch. It lies opposite the feed opening and is more effective upon the loose material as fed to the machine. The pitch of the remaining vane flights decreases until those at the lower or discharge end, where the material becomes most dense, are quite slow, compared to the early flight 24a. The peripheral edge portions of all flights of course closely hug the inner surface of the barrel 11.

Abutment pins or members 25 are screwed through threaded openings in two oppositely disposed bars 26 welded in place between the inner and the outer barrel tubes 11, 12, dividing the cavity 13 into two semicylindrical halves and enabling the pins to be adjusted or replaced from the outside of the barrel, by direct application of a tool, notwithstanding its jacket construction.

The material to be compressed is fed to the machine, by introducing it into a hopper 27 welded to and at one side of the barrel and communicating with the working space below plate 28 by way of the feeding opening 28.

Both tubes 11, 12 of the barrel terminate at their lower ends at shelf 6, so that the pressing space opens or discharges above the sloping discharge plate 8 which directs the finished or treated material outwardly from the machine. Screw shaft 21, however, extends through plate 8 and shelf 7 and is journaled in the tube 10 as a bearing. Its entire weight is supported from above by the plate 11a and the press frame on which said plate is mounted.

Each of the semicylindrical halves of the chamber 13 between tubes 11, 12 is provided at its upper and lower ends with a pipe 29 by means of which either steam for heating or water or other fluid agent for cooling may be circulated through said cavity, usually from bottom to top. Thus a heating or cooling effect may be applied directly to the external surface of the inner barrel member 11 and close to the tube like mass of material being treated under pressure.

Preferably the machine is designed so that a similar effect may be applied to the tubular mass of material from the inside, through the tubular wall of the screw shaft. For this purpose a part of the frame, such as shelf 1, has rigidly secured thereto a depending bracket 30 having a bottom plate 31 on which is mounted a tube 32 concentrically disposed within shaft 21 but smaller, to provide an annular cavity 33, and somewhat shorter, stopping short of plug 20 at its upper end. The lower end of tube 32 is closed by a plug 34 having a threaded opening 35 to receive a pipe 36, and plate 31 supports a sleeve 37 having packing 38 and a side opening to receive pipe 39. Fluid may be supplied through pipe 39, filling the cavity 33 and exerting a cooling effect, and be discharged through tube 32 and by way of pipe 36. Heating steam may be similarly circulated.

Usually sleeve 37 is mounted upon a supplemental disk 40 rotatably adjustable on disk 31 by loosening the clamping bolts 41 passing through short circumferential slots in plate 31. This enables the water supply pipe 39 to be brought in from any direction.

The apparatus described is capable of use for various purposes and the invention is not limited

to any particular use. One manner of use may be referred to as illustrative and in no sense of limitation.

In the treatment of corn cobs or other cellulosic material for conversion into sugar or alcohol, the cellulosic material, usually finely divided or comminuted, is sprayed or otherwise mixed with dilute acid. The material so wetted is fed to the hopper 27 while the machine is in operation with the screw shaft rotating in the proper direction to move the material downwardly. It enters the annular cavity 23, is engaged by the vane flights 24a, 24, and is caused to move downwardly, experiencing increased compression, while so moving, by the decrease in pitch of the successive flights. Pins 25 prevent the material from rotating with the screw and compel it to move forward. By properly proportioning the machine as to length and diameter of screw shaft, rate of rotation, etc., the material is held under compression in the machine for a desired period, within reasonable limits. While under compression it may be subjected to any desired temperature effect by the use of either or both of the jacket cavities, one within and the outside of the moving tubular column of material. Barrel 11 is imperforate. Therefore no liquid is expressed from the mass, but the entire mass is discharged along the sloping shelf 8 and delivered to any suitable container or chute or in a pile on the floor.

In one particular machine used in the manner described, maximum pressure may be secured up to 400 pounds per square inch. The worm shaft turns at 4 R. P. M. with a capacity of 500 pounds, per hour using $2\frac{1}{2}$ to $2\frac{3}{4}$ H. P. Pressure variations may be secured by using different worm shafts with various pitches of worm flights, or by varying the moisture content of the material entering the press. For example, the same material, e. g., corn cobs, containing 75% moisture, developed on 20-30 pounds per square inch, whereas reduction of the moisture content to 50% increased the possible pressure to 300 pounds per square inch. Pressure may be also controlled by utilizing an ordinary adjustable choke mechanism at the outlet, such as shown, for example, in Patent No. 2,178,714, granted November 7, 1939, to R. T. Anderson for Press.

The apparatus described is of relatively simple form, develops high pressures, applies heat or a cooling effect to the material both internally and externally, has high capacity and is durable in service. The weight of all heavy parts is supported from the upper platform and the several shelves. Upward thrust is transmitted to the transmission mechanism directly through shaft 16 where it bottoms in its recess, and not through pin 22. The screw shaft is of relatively light weight, because tubular, and yet is strong enough for its purpose. Repairs and adjustments, as of pins 25, are simple and may be made by simple operations. Radial thrust on the bearings is practically eliminated by vertical disposition of the screw shaft, such arrangement also utilizing gravity to assist in feeding the material and forcing it downward along the shaft through the compression chamber. It also enables the proper lubricating oil level readily to be maintained in the transmission. But, under certain conditions, the axis of the worm shaft may be horizontal, as will be readily understood.

Other advantages of the invention will be apparent to those skilled in the art.

What I claim is:

1. An impregnating machine, comprising an upright frame supporting an imperforate jacketed cylindrical vertical barrel open at its lower end and having a material feed opening on one side near its upper end, a hollow imperforate worm shaft coaxial with the barrel and provided within it with worm flights decreasing in pitch downwardly, the upper end of said shaft being closed and having a member extending through the upper end of the barrel and from which it depends and by means of which it is driven and its lower end having a plain cylindrical portion free of worm flights extending below the barrel, and a radial sleeve bearing mounted on the frame at a level below the lower end of the barrel and through and beyond which the plain cylindrical portion of said shaft extends.

2. An impregnating machine, comprising an upright frame supporting an imperforate jacketed cylindrical vertical barrel open at its lower end and having a material feed opening on one side near its upper end, a hollow imperforate worm shaft coaxial with the barrel and provided within it with worm flights decreasing in pitch downwardly, the upper end of said shaft being closed and having a member extending through the upper end of the barrel and from which it depends and by means of which it is driven and its lower end having a plain cylindrical portion free of worm flights extending below the barrel, a radial sleeve bearing mounted on the frame at a level below the lower end of the barrel and through and beyond which the plain cylindrical portion of said shaft extends, and an inclined delivery shelf also mounted on the frame between the lower end of the barrel and the lower end of said bearing by means of which the material discharged from the barrel is deflected laterally.

3. An impregnating machine, comprising an upright frame supporting an imperforate jacketed cylindrical vertical barrel open at its lower end and having a material feed opening on one side near its upper end, a hollow imperforate worm shaft coaxial with the barrel and provided within it with worm flights decreasing in pitch downwardly, the upper end of said shaft being closed and having a member extending through the upper end of the barrel and from which it depends and by means of which it is driven and its lower end having a plain cylindrical portion free of worm flights extending below the barrel, a radial sleeve bearing mounted on the frame at a level below the lower end of the barrel and through and beyond which the plain cylindrical portion of said shaft extends, a packing sleeve surrounding the worm shaft below said radial bearing and supported on the frame, and a fluid circulation tube of smaller external diameter than the internal diameter of the shaft, said tube having its upper end open and being supported on said sleeve in position coaxial with said shaft to provide inner and outer channels within the shaft through which fluid may be circulated.

4. An impregnating machine, comprising an

upright frame supporting an imperforate jacketed cylindrical vertical barrel open at its lower end and having a material feed opening on one side near its upper end, a hollow imperforate worm shaft coaxial with the barrel and provided within it with worm flights decreasing in pitch downwardly, the upper end of said shaft being closed and having a member extending through the upper end of the barrel from which it depends and by means of which it is driven and its lower end having a plain cylindrical portion free of worm flights extending below the barrel, a radial sleeve bearing mounted on the frame at a level below the lower end of the barrel and through and beyond which the plain cylindrical portion of said shaft extends, an inclined delivery shelf also mounted on the frame between the lower end of the barrel and the lower end of said bearing by means of which the material discharged from the barrel is deflected laterally, a packing sleeve surrounding the worm shaft below said radial bearing and supported on the frame, and a fluid circulation tube of smaller external diameter than the internal diameter of the shaft, said tube having its upper end open and being supported on said sleeve in position coaxial with said shaft to provide inner and outer channels within the shaft through which fluid may be circulated.

5. An impregnating machine, comprising a frame supporting a cylindrical vertical barrel, a worm shaft coaxial with said barrel and having longitudinally spaced separate worm flights located and rotatable within the barrel, said barrel consisting of two tubular wall members spaced apart radially to provide an annular jacket space between them through which fluid may be circulated, a filler member extending across the jacket space from one wall member to the other and having a sealed connection to each wall member, said filler member and the two walls which it connects being provided with a through opening, and a knife member mounted in said opening with its inner end extending into the space between two adjacent worm flights for preventing rotation of the material with the worm shaft, the outer end of said knife member being accessible from the outside of the outer wall member of the barrel for removing or otherwise manipulating the same.
